Zito

[11] Patent Number: Des. 407,138

[45] Date of Patent: **Mar. 23, 1999

[54] LIQUID CO₂ REFILLING DEVICE

4,936,343 6/1990 Pruitt et al. 137/571
5,022,364 6/1991 Phillips 137/557
5,113,905 5/1992 Pruitt et al. 137/571
5,797,419 8/1998 Perrott et al. 137/624.11

[75] Inventor: **Richard R. Zito**, Tucson, Ariz.

Primary Examiner—Alan P. Douglas
Assistant Examiner—Robin V. Taylor

[73] Assignee: **Richard R. Zito R & D Corp.**,
Tucson, Ariz.

[57] CLAIM

[**] Term: **14 Years**

The ornamental design for a liquid CO₂ refilling device, as shown.

[21] Appl. No.: **67,643**

DESCRIPTION

[22] Filed: **Mar. 3, 1997**

FIG. 1 is a perspective view;
FIG. 2 is a side view;
FIG. 3 is an opposite side view;
FIG. 4 is a front view;
FIG. 5 is a back view;
FIG. 6 is a top view; and,
FIG. 7 is a bottom view.
